UNITED STATES PATENT OFFICE.

RICHARD F. SCHULZKE, OF SALT LAKE CITY, UTAH.

STEPLADDER.

Application filed January 20, 1922. Serial No. 530,703.

To all whom it may concern:

Be it known that I, RICHARD F. SCHULZKE, a citizen of the United States, residing at Salt Lake City, in the county of Salt Lake and State of Utah, have invented certain new and useful Improvements in Stepladders, of which the following is a specification.

This invention relates to improvements in ladders, and the primary object of the invention is the provision of a step ladder constructed in such a manner as to insure the stability thereof when in its set up spread position, said ladder including novel means for associating the prop section with the main section, whereby the prop section will effectively cooperate with the main section for supporting weight when placed on the ladder.

20 A further object of the invention is the provision of a novel means for automatically locking the prop section with the main section, when the prop section is moved to its spread position, said means preventing the collapsing of the ladder and the creeping thereof when weight is placed upon the same.

25 A further object of the invention is the provision of an improved step ladder embodying a main section and a prop section, the upper end of the prop section being slidably connected with the main section and arranged to frictionally lock therewith when moved to its spread position, said prop section including novel guiding means for engaging the main section, and novel means for supporting the main section when the ladder is in its set up position, the prop section being adapted to overlie the main section when in its collapsed position, whereby 30 breakage of the parts of the ladder will be prevented.

35 A still further object of the invention is the provision of an improved step ladder of the above character, which is durable and efficient in use, one that is simple and easy to manufacture, and one which can be placed upon the market at a reasonable cost.

With these and other objects in view, the invention consists in the novel construction, arrangement and formation of parts, as will be hereinafter more specifically described, claimed and illustrated in the accompanying drawings, forming a part of this specification, in which drawings:

Figure 1 is a perspective view of the step

ladder, showing the same in its set up position.

Figure 2 is a longitudinal section through the ladder, showing the same in its collapsed position.

Figure 3 is a front elevation of the ladder, showing the same in its folded position, parts of the ladder being broken away.

Figure 4 is a fragmentary front elevation of the ladder, showing the same in its set up position.

Figure 5 is a fragmentary longitudinal section through the ladder, showing the same in its set up position.

Figure 6 is a detail transverse section through the ladder, taken on the line 6-6 of Figure 5.

Referring to the drawings in detail, wherein similar reference characters designate corresponding parts throughout the several views, the letter A generally indicates the improved ladder, which includes the main section B; and the prop section C.

The main section B is in the nature of a flight of steps, and includes the side stringers 10, and the cross steps or rungs 11. The inner faces of the stringers 10 may be grooved for the reception of the terminals of the steps, and suitable fastening elements 12 may be inserted through the outer face of the stringers 10 into the steps. If desired, every other step 11 may be braced by suitable brackets 13. The upper ends of the stringers 10 may have secured thereto the platform 14, which can be braced by the depending side pieces 15, which are in turn secured to the stringers. If desirable, the stringers 10 may be provided with the longitudinally extending slots 16 in the usual manner. The side faces of the stringers 10 directly below the side pieces 15 have secured thereto wedges 17, the purpose of which will be hereinafter more fully described. The tapered terminals of the wedges 17 are positioned lowermost and form friction lock seats for the prop section C.

The prop section C includes the standards or legs 18, which may be braced or connected together in any preferred manner, such as by diagonally extending braces 19 and cross strips or braces 20 and 21. The upper cross brace 20 is adapted to engage the lower edges of the side pieces 15, when the ladder is moved to its spread set up position, and this brace forms a seat for said side pieces and tends to support the weight of the

ladder. This brace 20 rests upon the upper ends of the diagonal brace strips or bars 19, and thus these diagonal brace bars or strips form a means for supporting or bracing the said brace 20.

The upper ends of the standards or legs 18 are connected by a transversely extending rod 22, which extends through the slots 16 formed in the stringers 10 and this rod 22 10 performs the triple function of bracing and connecting the legs or standards 18, forming a guide for the prop section when the same is being moved to and from its set up position and for forming a support for engaging 15 the side pieces 15. The terminals of this rod 22 may be flattened to form feet 23, which can be bent around the legs or standards 18 and securely connected thereto by means of pins, rivets or the like 24. 20 The lower terminal of the prop section C is connected with the main section B by spreader or stretcher arms 25 and 26. These spreader arms 25 and 26 may be bound by metallic cuffs 27, which form means for 25 preventing the splitting of said arms. The extreme lower ends of the arms are pivotally connected to the legs or standards 18 by means of pivot pins 28, which are extended through the cuffs 27. The upper 30 ends of the stretcher arms 25 and 26 are pivotally connected to the stringers 10 at a point above the transverse center of the main section B, by means of pivot pins 29, which also extend through the metallic cuffs 35 27, carried by the upper ends of the said arms. The spreader or stretcher arms 25 and 26 form an important means for adding stability to the ladder as the prop section is thoroughly braced or connected with the 40 main section by said arms, and the creeping or walking of the ladder when weight is placed upon the same is prevented. When the prop section is moved to its extended position, the upper terminals of the legs or standards 18 which extend beyond the cross 45 brace 20 will be forced into engagement with the wedges 17 and these legs or standards will bind into frictional tight engagement therewith, which will lock the prop section 50 in its extended operative position in relation to the main section B. When the ladder is in its set up position, the same can be conveniently moved around to various positions, without danger of the collapsing of 55 the ladder, and when weight is placed upon the main section B, the same will have a tendency to move to its spread position in relation to the prop, thereby insuring against the collapsing of the ladder when 60 the same is in use.

When the ladder is moved to its extreme open set up position, the upper cross brace 20 will be in engagement with the lower edge of the depending side brace pieces 15, as will also the cross rod 22, and thus the

prop section will form an effective means for supporting weight, which may be placed upon the ladder. Not only do the wedges 17 form means for locking the prop section in its set up position, in relation to the 70 main section B, but also form means for precluding lateral movement between the prop section C and the main section B.

From the foregoing description, it can be seen that an improved and efficient step ladder has been provided, in which the likelihood of the same collapsing when in use, is absolutely precluded, and which embodies means for automatically locking the prop section in its set up position in relation to 80 the main section, when the prop section has been swung outwardly to its operative position, when the ladder is in use.

The standards 18 are adapted to lie on opposite sides of the stringers 10, when the 85 ladder is in its collapsed position, as clearly shown in Figures 2 and 3 of the drawings.

Changes in details may be made without departing from the spirit or scope of this invention; but,

I claim:

1. A ladder comprising a main section having side stringers and steps secured between said stringers, the stringers being provided with longitudinally extending slots 95 above the upper step, a platform upon the upper ends of said stringers and having ends extending beyond the stringers, and side boards secured to the outer side faces of the upper end portions of said stringers and 100 engaging the under faces of the extended ends of said platform, a prop having side legs, a rod connecting the upper ends of said legs and extending through the slots in said stringers to slidably and pivotally mount the prop, a cross strip carried by the upper end portions of said legs, said cross strip and said rod being adapted to engage the lower edges of the end boards and brace the side boards and platform when the prop is 105 moved to an operative position, downwardly tapered wedges secured to the outer faces of the upper end portions of said stringers and adapted to engage the legs when the prop is moved to an operative position and frictionally hold the prop in the operative position, and braces pivotally connected with the lower ends of the legs and with the stringers intermediate the lengths thereof.

2. A ladder comprising a main section having side stringers and steps secured to said stringers, the stringers being provided with longitudinally extending slots above the upper steps, a platform upon the upper ends of said stringers, and side boards secured to said stringers and the under face of the platform adjacent the ends thereof; a prop including side legs and a cross strip secured to the upper end portions of said legs, a rod extending between the stringers 120 125 130

and having its ends projecting through the slots therein and secured about the upper end portions of said legs and serving to slidably and pivotally mount the prop, the rod and cross strip being adapted to engage the lower edges of the side boards when the prop is moved upwardly and swung to an operative position, braces for limiting swinging movement of the prop away from the main section, and wedging means for frictionally holding the prop swung outwardly to an operative position.

RICHARD F. SCHULZKE.
